UNITED STATES PATENT OFFICE.

GEORGE T. SOUTHGATE, OF BROOKLYN, NEW YORK.

RESISTANCE MATERIAL.

1,297,744.

Specification of Letters Patent.

Patented Mar. 18, 1919.

Application filed April 19, 1917. Serial No. 163,102.

To all whom it may concern:

Be it known that I, GEORGE T. SOUTHGATE, a citizen of the United States, residing at Brooklyn, in the county of Kings and State 5 of New York, have invented certain new and useful Improvements in Resistance Materials; and I do hereby declare the following to be a full, clear, and exact description of the invention, such as will enable others 10 skilled in the art to which it appertains to make and use the same.

My invention relates to electric resistance materials.

I have discovered that the compound 15 known as cuprous sulfid and designated by the chemical formula Cu_2S possesses a high resistance; its resistivity being about 100 ohms per cubic centimeter. I have furthermore discovered that its resistance is permanent 20 at a given temperature and is not permanently affected by changes in its temperature, and also that metallic terminals may be formed out of the body of the cuprous sulfid. I have made use of these properties of 25 said compound in the resistance element for the lightning arrester shown in the accompanying drawing and hereinafter described and claimed.

In the drawing, 1 represents the line, or 30 other conductor, that is to be protected against lightning, or other high tension discharges.

2 represents a conductor which connects the line 1 with one horn 3 of the main air 35 gap. The other horn 4 of the main air gap is connected by the conductor 5 with the metallic terminal 6.

The horns 3 and 4 are preferably solid and formed of iron, but they may be hollow 40 and formed of any suitable metal, and the distance between said horns may be varied to suit the initial striking potential of the high tension discharge.

I preferably form the cuprous sulfid into 45 a solid cylinder such as 7 and form the metallic terminal 6 on one end thereof.

On the other end of the cylinder 7 I form 50 a second metallic terminal 8 and connect the terminal 8 to the ground 10 by the conductor 9.

The terminals 6 and 8 may be attached to the cylinder 7 in any approved manner, but my preferred process for forming said terminal consists in providing a mold for the

cylinder 7 having a substance therein where 55 the terminals 6 and 8 are to be formed that will combine with the sulfur of the cuprous sulfid and reduce the latter to metallic copper.

In carrying out my process I provide a 60 composite mold for the cylinder 7.

Said mold for the portion of said cylinder between the terminals 6 and 8 is composed of any inert material, among which, either 65 carborundum, corundum or silicon is suitable.

The parts of the mold for the terminals 6 and 8 are composed of any material that will combine with the sulfur of the cuprous sulfid and reduce the surface of the latter to 70 metallic copper.

A suitable material for causing said reduction of the cuprous sulfid is graphite, and the reduction is more readily effected if the mold is heated. The mold may be heated 75 until the graphite is incandescent if desired.

Otherwise the mold is made as usual for metal casting and the cuprous sulfid is melted and poured therein.

To the terminals 6 and 8 I electrically attach in any suitable manner the metallic rods 11—11 projecting radially from the cylindrical surfaces of said terminals, and at the outer ends of the rods 11—11 I secure in electrical connection therewith the 85 metallic rods 12—12, the adjacent ends of said rods terminating in the metallic balls 13—13, thus providing an auxiliary spark gap in shunt to the resistor 7 that is very susceptible to sparking when subjected to a 90 high frequency charge.

The operation of my improved lightning arrester is as follows:

A high tension discharge upon the conductor 1 will travel along the conductor 2 95 to the horn 3, thence across the air gap to the horn 4 and thence along the conductor 5 to the terminal 6.

Should the discharge be of high frequency or very high tension, during the first instant 100 of said discharge, it will pass along the upper rods 11 and 12 to the upper ball 13, thence across the air gap to the lower ball 13, thence along the lower rods 12 and 11 to the cap 8, and thence along the conductor 105 9 to the ground 10.

Thus the surge current passes with a minimum of impedance to the ground and the

resistor 7 is protected from energy that would otherwise be liberated therein, and the spark in the auxiliary air gap is quickly extinguished by the shunting action of the 5 resistor 7.

After the first instant of a discharge of very high tension, and during the whole period of a discharge of medium high tension, the discharge will pass from the terminal 10 6 through my resistance element 7 to the terminal 8 and thence along the conductor 9 to the ground 10.

The passage of the high tension discharge across the air gap between the horns 3 and 15 4 will cause the establishment of an arc which will be sustained by the dynamic current, should such a current exist in the conductor 1.

When said arc is established the dynamic 20 current will pass through the resistance element on its way to the ground 10, and, owing to the high resistance of the resistance

element 7, the line voltage will be unable to maintain an arc between the horns 3 and 4.

I have shown the resistance element as a 25 solid cylinder, but it is evident that it may be hollow, or that rods of other cross sectional forms may be used.

I claim:—

1. A resistance element composed of cuprous sulfid having the formula Cu_2S . 30

2. A resistance element composed of cuprous sulfid and provided with metallic terminals.

3. A resistance element composed of cuprous sulfid having the formula Cu_2S and 35 provided with metallic terminals formed from the body of the cuprous sulfid.

4. A resistance element composed of a metallic compound and provided with metallic terminals formed from the body of 40 said compound.

In testimony whereof, I affix my signature.
GEORGE T. SOUTHGATE.
